GAS GENERATOR FOR FUMIGATION PURPOSE

Ted Forsberg, San Leandro, Calif.

Application August 21, 1933, Serial No. 686,142
Renewed March 20, 1935

1 Claim. (Cl. 99—18)

This invention relates to a device for generating gas to be used in fumigating and has as its object the provision of such a device which may be used without danger to the operator.

5 The invention together with its numerous objects and advantages will be best understood from a study of the following description taken in connection with the accompanying drawings wherein is illustrated a preferred embodiment
10 of the invention.

10 of the invention.
It is to be understood at the outset that it is
in no wise intended to restrict the invention to
the precise details of construction, combination
and arrangement of elements, other than may
15 be necessary to meet the requirements of the
prior art and scope of the appended claim.

In the drawings:

Figure 1 is an elevational view of a generator embodying the features of the present invention.

20 Figure 2 is a vertical sectional view, on an enlarged scale, through the device.

Figure 3 is a horizontal sectional view taken substantially on the line 3—3 of Figure 2.

Figure 4 is a plan view of a pan or plate to be
hereinafter more fully referred to.

Referring to the drawings by reference numerals it will be seen that the gas generator comprises a tank 5 of metal or other suitable material, and of acid resisting qualities. The tank 5 may be of any desired size, the size of the tank obviously determining the thickness of the walls thereof.

For the top of the tank 5 there is provided a shell like cover or cap designated generally by the reference numeral 6. Cap 6 comprises a substantially frusto-conical plate 7 and a flat inner end plate 8 connected with the plate 7 and spaced therefrom through the medium of spaced parallel partitions 9. The partitions 9 are arranged as clearly shown in Figure 3, each partition being fixed at one end to the cover and having its other end spaced from a corresponding portion of the cover with each successive partition fixed at alternate ends for establishing communication between the spaces formed by the partitions in a manner to provide, within the chamber 10 formed within the cover or lid 6 a tortuous passage leading from the inlet 11 provided for the chamber 10 in the plate 8, to the outlet 12 in the top plate 7.

The lid 6 is also provided with a filling neck 13 and the inner end is secured to the plate 8 in any suitable manner, preferably as by being integral therewith. The filling neck 13 extends through the plate 1 of the lid and is provided with

a suitable closure 14. A valve 15 is connected with the outlet 12 and a hose 16 is connected at one end with the valve 15. The free end of the hose 16 is provided with any suitable type of spray nozzle (not shown) for directing the gas into the space or area to be fumigated.

A rod 17 is slidable through a gland structure 18 provided in the cap 6; and to secure the rod 17 at the desired adjustment there is provided thereon a stop collar 19 with which is associated 10 a wing nut 20 to secure the collar at the desired position on the rod 17. The collar 19 is engageable with the gland 18 and cooperates therewith for supporting the rod 17 at the desired elevation with respect to the bottom of the tank 15 or container 5.

Provided on the lower or inner end of the rod 17 is a relatively shallow pan or plate 21 the bottom of which is perforated as shown.

In actual practice the tank or receptacle 5 is adapted to contain any suitable liquid chemical 22, the same being introduced into the container 5 through the filling neck 13 and seeks a level approximating that suggested in the drawings. The shallow pan 21 is adapted to contain dry chemicals 23, and normally pan 21 is disposed above the liquid level. To form the fumigating gas rod 17 is moved downwardly for lowering the pan 21 into the liquid chemical 22 so that the dry chemicals carried by the pan 22 will combine with the liquid chemicals to generate the gas, which latter, under its own pressure passes into the chamber 10 through the inlet 11. In seeking the outlet 12 the gas in the chamber 10 is caused to travel in a circuitous or tortuous path provided by the partition 9. The provision of the baffles insures thorough separation of the liquid or condensed gas particles. Manifestly the discharge of gas from the chamber 10 through the hose 16 is manually controlled by the valve 15.

The dry chemicals are in the form of solid particles so that they cannot pass through the perforations in the pan and even if the pan is wet, the moisture will have little or no effect on the particles so that the operator will have plenty of time in which to replace the cap 14, after the particles have been placed in the pan, before any gas can form. However, if desired, the operator may wait until the pan has dried before placing the particles therein. 45 50

It will be apparent that I have provided a gas generator which is of extremely simple construction at the same time will be thoroughly practical and efficient in use and operation. 55

Having thus described my invention, what I claim as new is:

In a generator of the class described, a tank adapted to contain a liquid chemical, a cover for the tank having means for connecting a conduit hose thereto, a rod slidable axially through said cover, and a pan on the inner end of the rod adapted to contain a dry chemical, said cover

provided with a gas chamber and a gas inlet for establishing communication between said chamber and the interior of said tank, and partitions arranged in said gas chamber between said gas inlet and the hose connection and providing a tortuous gas passage for the conducting of gas through said chamber.

TED FORSBERG.
